[57] CLAIM

The ornamental design for a scent dispenser attachable to a hunter's boot, as shown and described.

DESCRIPTION

FIG. 1 is a front elevational view of the scent dispenser attachable to a hunter's boot showing my new design; FIG. 2 is a rear elevational view thereof; FIG. 3 is a right side view thereof; FIG. 4 is a left side view thereof; FIG. 5 is a top plan view thereof; and, FIG. 6 is a bottom plan view thereof.

The cross-hatching represents conventional fabric and is understood to extend uniformly throughout the areas represented.
